UNITED STATES PATENT OFFICE.

WILLIAM H. CAMERON, OF PITTSBURGH, PENNSYLVANIA, ASSIGNOR TO STANDARD CHEMICAL COMPANY, OF PITTSBURGH, PENNSYLVANIA.

THERAPEUTIC APPLICATOR.

Application filed September 15, 1922. Serial No. 588,386.

To all whom it may concern:

Be it known that I, WILLIAM H. CAMERON, a citizen of the United States, and a resident of Pittsburgh, in the county of 5 Allegheny and State of Pennsylvania, have invented certain new and useful Improvements in Therapeutic Applicators; and I do hereby declare the following to be a full, clear, and exact description of the invention, 10 such as will enable others skilled in the art to which it appertains to make and use the same.

This invention relates to improvements in therapeutic applicators and more particularly to holding means for a plaque which carries radio-active material.

One object of my present invention is to provide simple and efficient means for adjustably connecting the body portion of the 20 holder with a handle member, whereby the radio-active plaque may be adjusted at any desired angle with respect to the handle member, and fixed in the position to which it may be adjusted.

With this and other objects in view, the invention consists in certain novel features of construction and combinations of parts as hereinafter set forth and pointed out in the 25 claim.

In the accompanying drawings, Figure 1 is a view illustrating my invention. Figure 2 is a sectional view, and Figure 3 is a sectional view taken at right angles to Figure 2.

In the drawings, 1 represents a plaque 35 comprising a metal container in which radio-active glaze is located, said glaze being such as disclosed in Letters-Patent to C. H. Viol January 2nd 1917 and designated by No. 1,210,731.

A holder for the plaque is represented at 40 2 and is made with a rear end flange 3 and side flanges 4, the latter being slotted at 5 so that the forward end portions of said flanges will form resilient fingers 6 to grasp the plaque and hold the same against ac-

idental displacement. The rear end flange of the holder may be provided with a hole 7 to permit the introduction of a suitable tool for facilitating the removal of the plaque.

The holder 2 is provided on its back with parallel ears 8—8 between which a nut 9 is loosely mounted on a pin 10 fixed to said ears and extending from one to the other. This nut receives the threaded shank 11 of 55 a handle stem 12, and the latter is threaded at its other end and enters a threaded socket 13 in a handle 14.

The plaque holder is thus pivotally connected with a handle member and may be 60 readily adjusted to any desired angle relatively to the axis of the handle, in which adjustment it may be held rigidly by turning the handle stem until the threaded shank 11 binds tightly against the pin 10 on which 65 the holder is mounted.

With the use of my improvements, the applicator plaque may be readily adjusted to and thus held rigidly in any position which will best facilitate its application to a patient in a given case.

Having fully described my invention what I claim as new and desire to secure by Letters-Patent, is:

In a radio-active applicator, the combination with a holder, a radio-active plaque held therein, a nut, a fixed pivot pin connecting said nut with the back portion of the holder, and a handle member having a threaded portion entering said nut and 75 adapted to engage said pivot pin to lock the holder in adjusted position.

In testimony whereof, I have signed this specification in the presence of two subscribing witnesses.

WILLIAM H. CAMERON.

Witnesses:

CHARLES H. VIOLE,
P. F. HAGUE.
